UNITED STATES PATENT OFFICE.

SAMUEL P. WYRFEL, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC-LAMP SOCKET.

Application filed June 15, 1923. Serial No. 645,656.

To all whom it may concern:

Be it known that I, SAMUEL P. WYRFEL, a citizen of the United States of America, residing at Hartford, in the county of Hartford and State of Connecticut, have invented certain new and useful Improvements in Electric-Lamp Sockets, of which the following is a specification.

My invention relates to electric lamp sockets 10 threaded to receive shade holders, and more particularly to weatherproof shade-holding sockets. Among the advantages of my socket are its simplicity of construction and manufacture and its superior weather- 15 proof qualities.

In the drawings—

Fig. 1 is an elevation of a socket embodying my invention, a shadeholder and shade being shown applied thereto;

Fig. 2 is a bottom plan view of the socket with a shadeholder attached but without the shade;

Fig. 3 is an elevation partly broken away of the partly finished blank from which the shell of the socket is formed;

Fig. 4 is a perspective view of the finished socket shell; while

Fig. 5 is a sectional view on a larger scale, showing more clearly the manner in which the shadeholder is securely held to the socket shell.

Fig. 6 is a view of a modification.

The ordinary method of attaching a shadeholder to a lamp socket by means of threads 35 or a bead on the outside of the socket shell does not produce a satisfactory waterproof joint between the shell and holder, with the result that in the past metal weatherproof sockets have had their shadeholders suspended from inside the open end of the socket or from a canopy covering the whole socket. My invention provides an effective and waterproof joint on the exterior of the socket shell and not only eliminates all special parts but is simple and economical to manufacture. I accomplish this by the arrangement of threads and bead whose formation on the socket shell I shall now describe.

In making the socket shell a large bead 6 is first rolled out on the cup-shaped blank 7 near what is to be the lower end of the shell, into somewhat the form shown in Fig. 3. The edges of this large rounded bead 6 are

then squeezed together and it is pressed into 55 a downwardly overhanging bead 8 such as shown in Fig. 5. Threads 9 are formed on the shell a short distance below the bead by any desired method, the bottom 15 (Fig. 3) cut out and the shell finished in the usual 60 manner and assembled with the rest of the socket 10.

A plain light one-piece shadeholder 11 can be used on my socket, and it should have threads 12 on its central collar 13 to engage 65 the threads 9 on the shell. When the shadeholder is screwed onto the socket the downwardly overhanging bead 8 first touches the sloping surface of the shadeholder at a point 14 a little distance from the central 70 collar 13. If the shadeholder is screwed on a little further it tends to lock the threads of the shell and collar together, and at the same time insure a close fitting and watertight joint at 14. This wedging is assisted 75 by the resiliency of the shadeholder. It should also be noted that all external surfaces and the surface of the shadeholder under the bead will shed moisture readily.

I am aware that sockets have been heretofore known with external threads and beads on their lower ends, but as far as I am aware this is the first socket combining the thread and bead in which they cooperate to form a really waterproof joint. The formation of 80 a downwardly overhanging hollow bead from the shell itself is also novel.

It will be apparent that this invention may be applied to all sockets, whether metal or composition, weatherproof or interior.

Although my improved socket shell with downwardly overhanging bead is especially useful in connection with a shadeholder with sloping surface engaging the lower 95 outer edge of the bead as illustrated in Figs. 1 and 5, it may be employed in connection with other constructions, such for instance as the reflector or shade shown in Fig. 6 where an adapter or holder 15 is secured to a reflector or shade 16 and has its upper end threaded at 17 to screw onto the outside of the threaded end 9 below the bead 8. By reason of the downward overhang of this bead 8 the rain can not get to the joint.

What I claim is—

1. A lamp socket shell having external threads on it, with a downwardly overhang-

- ing hollow bead above said threads, said threads and bead being adapted to form a weatherproof joint with a shadeholder.
2. A lamp socket shell having external threads on it, with a folded flange forming a downwardly overhanging hollow bead above said threads for the purposes set forth.
3. A lamp socket shell having external threads on it, with a downwardly overhanging hollow bead above said threads, in combination with a shadeholder having a resilient sloping surface substantially as described.
- 15 4. A lamp socket shell having external threads on it, in combination with a downwardly overhanging hollow bead above said threads, and a shadeholder adapted to wedge on said threads and against said hollow bead.
- 20 5. A lamp socket shell having external threads on it, in combination with a downwardly overhanging hollow bead above said
- threads, formed from the walls of said shell.
6. A lamp socket shell having external threads on it, with a downwardly overhanging hollow bead above said threads in combination with a shadeholder having a sloping resilient surface adapted to wedge against the bead substantially as described.
- 25 7. A metallic lamp socket shell having external threads on its lower end adapted to receive a shade holder, the lower end of said shell being bent inwardly below said threads for the purpose of holding a porcelain body, and a downwardly overhanging hollow bead above said threads in combination with a one piece shade holder made of resilient material adapted to screw on the threads of said shell and to wedge against said bead and having an upwardly sloping surface under said bead, substantially as described.
- 30 35 40

In testimony whereof I have signed my name to this specification.

SAMUEL P. WYRFEL.
